UNITED STATES PATENT OFFICE.

ROBERT DUGAN, OF NEW YORK, N. Y.

UMBRELLA-FIXTURE.

SPECIFICATION forming part of Letters Patent No. 276,788, dated May 1, 1883.
Application filed August 5, 1882. (No model.)

To all whom it may concern:

Be it known that I, ROBERT DUGAN, of the city, county, and State of New York, have invented a new and useful Improvement in Umbrella-Fixtures, of which the following is a full, clear, and exact description.

Reference is to be had to the accompanying drawings, forming a part of this specification, in which similar letters of reference indicate corresponding parts in all the figures.

Figure 1 is a sectional elevation of my improvement, the cover being removed. Fig. 2 is a bottom view of the upper part of the upper or stationary runner. Fig. 3 is a plan view of the lower part of the same. Fig. 4 is a bottom view of the upper part of the lower runner. Fig. 5 is a plan view of the lower part of the same. Fig. 6 is a side elevation of the upper runner. Fig. 7 is a side elevation of the lower runner.

The object of this invention is to promote the durability of umbrella-fixtures.

The invention consists in the lower runner, formed of the recessed and slotted ring, having a screw-thread in its inner surface, and the lower part having a flange around it, near its upper end, and a screw-thread around its upper end to adapt it to receive and hold the inner ends of the braces; and also in the combination, with the parts of the lower runner, of braces having balls upon their inner ends, whereby the said braces will be securely hinged to the said lower runner, as will be hereinafter fully described.

A indicates the stick, B the ribs, and C the braces, of an umbrella.

The upper or stationary runner is made in two parts, D E. The upper part, D, consists of a sleeve having a flange, F, formed around its lower end. The flange F has as many recesses G formed in its lower face as it is designed to use ribs B in the umbrella, to receive balls H, formed upon the inner ends of the said ribs B. The outer end of the flange F is slotted directly opposite each recess G to receive the ribs B. The lower end of the part D is rabbeted, and upon the shoulder of the

said rabbet is formed a screw-thread to fit into a screw-thread upon the upper end of the lower part, E. The lower part, E, of the runner consists of a sleeve having a flange, I, formed around it near its upper end. The flange I has slots J formed through it in such positions as to be directly opposite the recesses G of the flange F when the two parts D E are screwed together to receive the ribs B when the umbrella is closed.

The lower runner is made in two parts, K L. The upper part, K, consists of a ring having recesses M in its lower side to receive balls N, formed upon the inner ends of the braces C. The ring K has slots O formed in it opposite the recesses M to receive the braces C when the umbrella is closed. The ring K has a screw-thread formed in its inner surface to fit into a screw-thread formed upon the upper end of the lower part, L. The lower part, L, consists of a sleeve having a flange, P, formed around it, near its upper end, to serve as a seat to the upper part, K, and as a cap to keep the inner ends of the braces C in place in the recesses of the upper part, K.

With this construction the ribs B and braces C are securely held in the recesses of the two-part runners with great freedom of movement at the joints, which are cheap and more substantial, and less liable to injury by corrosion than the common joints, making the umbrella more durable in use.

Having thus described my invention, I claim as new and desire to secure by Letters Patent—

The ring K, having the recesses M on its lower side, the slots O opposite said recesses, and a thread on the inside, in combination with a sliding sleeve, L, having an external thread at upper end, and the flange P at right angles thereto, said flange forming a seat for the ring and a cap for the braces, as shown and described.

ROBERT DUGAN.
